UNITED STATES PATENT OFFICE.

FRANK W. HOWARD, OF NEW YORK, AND GEORGE B. CANNON, JR., OF BROOKLYN,
NEW YORK.

COMBINED HAT PROTECTOR AND ENVELOP.

1,375,511.

Specification of Letters Patent. Patented Apr. 19, 1921.

Application filed November 3, 1919. Serial No. 335,330.

To all whom it may concern:

Be it known that we, FRANK W. HOWARD and GEORGE B. CANNON, JR., citizens of the United States, residing in the city of New York, county of New York, and city of Brooklyn, county of Kings, respectively, and State of New York, have invented new and useful Improvements in Combined Hat Protectors and Envelops, of which the following is a specification.

This invention relates to a combined hat protector and covering for a raincoat.

The general object of the invention is to provide a hat protector having a construction which will enable it to be used as a covering for a folded raincoat, but which can be readily expanded into an open condition adapting it to form a covering to protect one's hat. The protector is preferably formed of waterproof material, such as waterproof paper, which is relatively inexpensive, and it is expected to be used with a raincoat, also formed of inexpensive waterproof material. Such a raincoat can be folded into a very small space and can be placed within the hat protector, so that the hat protector is folded and tied up about it, thereby forming a neat package. The hat protector is provided with a cord or cords which enable it to be tied or secured about the raincoat and which also operate, when the envelop is being used as a hat protector, to pass under one's chin to hold the hat protector over the hat. It is intended that these packages, consisting of a hat protector and a raincoat contained therein, will be kept in public places so as to be available to persons who are accidentally caught in the rain. The hat protector, of course, should be particularly useful to prevent injury to relatively expensive hats, such as worn by ladies; until used, the hat protector operates as an envelop for the raincoat which is to be worn with it.

Further objects of the invention will appear hereinafter.

The invention consists in the novel features, and in the general combination of parts to be particularly described herein-after, all of which contribute to produce a simple and efficient combined hat protector and envelop. A preferred embodiment of our invention will be particularly described in the following specification, while the

broad scope of our invention will be pointed out in the appended claims.

In the drawing,

Figure 1 is a plan showing the complete package in which the hat protector is performing the function of an envelop for a folded raincoat;

Fig. 2 is a perspective showing the hat protector and envelop unfolded and opened up so as to expose the folded raincoat;

Fig. 3 is a perspective illustrating the manner of using the hat protector;

Fig. 4 is a vertical section taken through the hat protector in its open condition;

Fig. 5 is a section upon an enlarged scale taken about on the line 5—5 of Fig. 2; and

Fig. 6 is a plan of a blank particularly illustrating the manner in which the blank is folded in order to give it the shape of a hat protector.

In practising the invention, we form a concavo-convex envelop (see Fig. 4), which is preferably constructed of inexpensive waterproof paper. This envelop has two side walls 2, which in the open position of the envelop, form a dihedral angle with each other. Fig. 2 shows one of these hat protectors lying open on its side so as to enable it to receive a raincoat 3 which is folded up into a neat package of substantially rectangular form. The two side walls 2 of the protector are connected together at a common folding edge 4. When the folded raincoat 3 has been laid in the open envelop as in Fig. 2, the upper side wall 2 is folded downwardly over the raincoat on the longitudinally disposed edge 4, and the protector is then folded on the lines 5, 5, 6 and 7 so that the end portions 8 of the side walls form outside flaps or folds 9 lying on the outside of the package. These portions of the protector are preferably provided with ribbons or cords 10 which may be passed around the package and tied together in a bow 11. (See Fig. 1.)

The side walls 2 are connected together at their end portions 8 in any suitable manner so as to give the protector a concavo-convex form. This is preferably accomplished by having the material in the end portions 8 overlap so as to form layers 12 which are connected together by fastening devices in the form of cardboard buttons 13 and eyelets 14. (See Fig. 5.) The cords may be

attached to these fastening devices. (See Fig. 1.)

Fig. 2 represents the hat protector as made from a one-piece blank of material, folded at its ends so as to form a plurality of the layers 12. We prefer, however to form the hat protector out of a one-piece blank having the general characteristics of the blank 15, shown in Fig. 6. This blank 10 is of oblong or oval form, having ends 16, the edges of which may be struck as an arc about a center 17. From these points 17, radial folding lines 18 are indicated which act as guides in folding the ends of the 15 blank into the layers or tapered plaits 12 which are formed out of the material lying between the lines 18.

After the raincoat has been put on, the hat protector 1 may be applied over one's 20 hat 19. (See Fig. 3.) In order to hold the hat protector on, each cord 10 is passed under the chin and its end is wrapped several times around the button 13, which is located at the opposite point on the hat protector.

25 This simple means for securing the cords enables them to be readily detached in order to take off the hat protector.

After using the raincoat and hat protector, the raincoat can be readily folded up 30 again and replaced within the protector, as an envelop, which may be then folded into a neat package as illustrated in Fig. 1.

It is understood that the embodiment of the invention described herein is only one 35 of the many embodiments our invention may take, and we do not wish to be limited in the practice of our invention nor in our claims, to the particular embodiment set forth.

40 What we claim and desire to secure by Letters Patent is:

1. A combined hat protector and covering 45 for a raincoat consisting of an envelop having two opposite elongated side walls connected together along a folding edge and connected together adjacent their ends so as to permit the side walls to swing apart and assume a position forming a dihedral angle to each other at said edge, thereby enabling the envelop to cover one's hat, said side walls operating to fold together to cover a folded raincoat, and cords attached to the envelop for securing the same about the folded raincoat, and having means for 55 attaching the same to opposite sides of the envelop, for securing the envelop in its open condition over one's hat.

2. A combined hat protector and covering 60 for a raincoat consisting of an envelop having two side walls connected together along

a folding edge and connected together adjacent their ends so as to permit the side walls to swing apart and assume a position forming a dihedral angle to each other at said edge, thereby enabling the envelop to cover 65 one's hat, said side walls operating to fold together to cover a folded raincoat, a cord attached to the envelop at one side of the same, and a button attached to the envelop at an opposite point, enabling the cord to 70 be passed under one's chin and wrapped around the button to secure the protector over one's hat, said cord operating as means for securing the envelop around a folded raincoat. 75

3. A combined hat protector and cover for a folded raincoat, consisting of a single elongated sheet of waterproof material, the material of the wall at each end of the sheet being disposed in overlapped layers, 80 means for attaching said layers together to give the protector a concavo-convex form with two opposite elongated walls connected together at a longitudinally disposed edge and forming a dihedral angle at said edge 85 to enable the protector to open and cover one's hat, a cord and means for attaching the cord to the protector at opposite ends thereof and adjacent said overlapped layers, said cord operating to connect the opposite 90 sides of the protector when worn over the hat, said opposite side walls operating to cover opposite sides of a folded raincoat, and said overlapped end portions operating to form opposite flaps to fold over the folded 95 raincoat and enable the protector to be secured by the cord as an envelop over the raincoat.

4. A combined hat protector and covering 100 for a folded raincoat, consisting of an envelop having two elongated oppositely disposed side walls connected together along a folded edge and forming a dihedral angle at said folded edge enabling the said side walls to open apart to facilitate the envelop's being applied over one's hat, said envelop having end portions connecting said side walls, each end portion having a fastener for a cord enabling the cord to secure the hat protector over one's hat, said walls operating 105 to cover opposite sides of a folded raincoat, and said end portions operating to form folded flaps connected by the cord when the cover forms an envelop for the raincoat. 110

115 In testimony whereof, we have hereunto set our hands.

FRANK W. HOWARD.
GEORGE B. CANNON, JR.
